Phi Beta Kappa Society.

WALL-OUTLET BOX

temple, Williams Lake, British Columbia, Canada.

Application October 9, 1950. Serial No. 189,159

In Canada May 23, 1950

2 Claims. (Cl. 220—36)

This invention relates to wall-outlet boxes, and the objects of the invention are:

1. To provide means for firmly clamping outlet boxes, adapted to contain electric switches, expeditiously and directly to a wall without the use of any attaching means penetrating the wall.
  2. To design a particular construction of box to carry out the objects of this invention.

A box within this invention comprises a body consisting of a back wall and two side walls integral therewith; removable end plates or walls removably associated with said box body and sprung into stable relationship with said back and side walls to close the ends thereof, plates integrally formed with each end plate or wall each of which plates carries a screw lying parallel thereto adjacent the outer side thereof, and a plate threaded on each of said screws and lying parallel to the plates carried by said end plates or walls whereby the box is directly clamped to the wall, as hereinafter more particularly explained.

Fig. 1 is a view of the box clamped to a wall, the usual cover plate not being shown.

Fig. 2 is a vertical section on the line 2-2, 25
Fig. 1.

Fig. 3 is a vertical section on the line 3-3, Fig. 2.

Fig. 4 is a vertical section on the line 4-4 of Fig. 5.

Fig. 5 is a plan view of the bottom of the box, and

FIG. 6 is an enlarged view showing one end plate of the box clamped to the wall, and the other end plate ready to be moved on its hinges and clamped to the wall.

In the drawings, like characters of reference refer to the same parts.

The box is preferably made of iron of the usual gauge, though the drawings, for clearness of illustration, show the various parts of the box made of heavier gauge.

The box body consists of a back wall 4, provided with the usual knock outs, and side walls 3, which may also be provided with knock outs (not shown) if desired.

Each wall 3, is provided at each end with an exterior flange 4, for the full size thereof, and the wall 2 is provided at each end with a flange 5, extending from one flange 4, to the other. The flanges 4 and 5 are in alignment.

To close each end of the box body, removable end plates or walls 6, are used. When these plates or walls 6, are in final position they are held snugly against the flanges 4, and 5, and hence the switch (not shown) is safely boxed.

Each end of a plate or wall 6, is provided at its inner end with a pair of spaced lugs 7. When a plate 6, is finally placed its lugs 7, each enter a slot 8, formed in the back wall 2 (Fig. 2). These lugs and slots act as hinges on which each end plate or wall 6, is moved.

As shown the placed lugs 1, overlie the wall 2. Each side wall 3, near each corner thereof, is provided with an inwardly-extending lug 16 (Fig. 3) so that as the plates 6, are moved into final position they will snap by the lugs 16, and be snugly held against the flanges 4, and 5.

Projecting beyond the inner surfaces of the side walls 3, are spaced pairs of lugs 9. These lugs limit the inward movement of the plates 6, towards each other.

Each plate or wall 6, is provided at its outer end with an outward horizontal flange 10. Each of these flanges carries a pair of spaced metal screws 11. A plate 12, has threaded engagement with a pair of screws 11, behind each flange 10, and each has a sliding contact with a plate or wall 6.

To mount the box, a hole 13, is cut in the wall 14, of the same size as the box. Before the box can be mounted the walls or plates 6, with their clamping devices, are placed within the box body each in the position shown at the bottom of Fig. 6, with the flange 10, and plate 12, spaced well apart. The box is then placed in the wall 14, to occupy the hole 13, and then one wall or plate 6, is pivoted on its lugs 7, and moved into the position shown at the top of Figure 6, so that the wall 14, adjacent this end will be located between the flange 10, and the plate 12. By tightening the screws 11, the plate 12, is brought snugly into contact with the inner side of the wall 14 and the flange 10, is drawn inwardly into close contact with the outer side of the wall 4 (Fig. 2). Thus these elements straddle the thickness of the wall material.

By manipulating the other end wall or plate, as described, the box will be fully clamped to the wall 14, without the use of any attaching means that penetrate the wall.

Holes 15, are formed in the flanges 10, to receive the screws used to attach the cover plate (not shown) to the box.

By means of this invention wall-boxes of this type are mounted in place firmly and securely and without any possibility of the grip of the clamping means impairing the wall.

Fastening means, such as screws and nails now commonly used to fasten outlet boxes in place invariably injure the wall and ultimately work loose.

While herein is described and illustrated the preferred form of invention it is obvious that various changes in construction of the box body and its parts may be made without departing from the spirit of the invention and the scope of the claims.

I claim:

1. In combination a wall-outlet box comprising a body consisting of an end apertured back wall provided at each end thereof with an exterior flange, said apertures being adjacent each flange, and two side walls integral with said back wall, each end of the side walls being provided with an inwardly-extending flange lying contactingly in alignment with the corresponding end flange of said back wall and further provided with an inwardly-extending lug in spaced relationship to said side wall end flanges; movable end plates, each provided at its inner end with a pair of external lugs positioned in the apertures in said back wall to form hinges therewith, the said end plates adapted to snap by the lugs carried by said side walls into contact with the flanges of said side walls and the flanges of said back wall to close the ends of said box; an external flange carried by each end plate and

adapted to contact the outer side of a supporting wall; a screw mounted in each of said last-mentioned flanges to constantly lie in parallel relationship to and beyond the outer side of said end plates, and a plate mounted on each of said screws in parallel relationship to the flanges carried by said end plates and adapted to be clamped against the underside of said supporting wall.

2. The combination as set forth in claim 1 wherein the side walls are provided with lugs adapted to limit the movement towards each other of the end plates when they are being manipulated to attach the box to a wall.

PHILLIP TEMPLE.
